US00D470595S

(12) **United States Design Patent** (10) Patent No.: **US D470,595 S**
Crisanti et al. (45) Date of Patent: ** Feb. 18, 2003

(54) **ASSAY DEVICE**

(76) Inventors: **Andrea Crisanti**, Department of Biology, Imperial College, London (GB), SW7 2AZ; **Uri Friedlander**, 20 Belsize Avenue, London (GB), NW3 4AU

(**) Term: **14 Years**

(21) Appl. No.: **29/149,495**

(22) Filed: **Oct. 10, 2001**

(30) **Foreign Application Priority Data**

Apr. 10, 2001 (GB) 2100991

(51) **LOC (7) Cl.** **24-02**

(52) **U.S. Cl.** **D24/216; D24/223; D24/224; D24/225**
